By Myers & Co, Atty

UNITED STATES PATENT OFFICE.

DANIEL B. PECK, OF JACKSON, MICHIGAN.

SPRING BED-BOTTOM.

SPECIFICATION forming part of Letters Patent No. 245,553, dated August 9, 1881.

Application filed April 28, 1881. (No model.)

To all whom it may concern:

Be it known that I, DANIEL B. PECK, a citizen of the United States, residing near Jackson, in the county of Jackson and State of Michigan, have invented certain new and useful Improvements in Spring Bed-Bottoms; and I do hereby declare the following to be a full, clear, and exact description of the invention, such as will enable others skilled in the art to 5
10 which it appertains to make and use the same, reference being had to the accompanying drawings, and to letters or figures of reference marked thereon, which form a part of this specification.

15 My invention relates to an improvement in bed-springs; and it consists in the vertical springs A A, horizontal springs B B, links C C, the slats D D, the supporting-springs E E, staples F F, in connection with hooks G G
20 for securing the springs to the slats, the novel arrangement of parts for forming a double vertical bed-spring, the peculiar structure of the parts for securing the springs together at their apex upon the same plane, and in the combination and arrangement of the parts, as herein-
25 after more fully shown and described.

In the drawings, Figure 1 is a plan view. Fig. 2 is a side elevation. Fig. 3 is a vertical section. Fig. 4 is a plan view, showing construction of the links; and Fig. 5 is a plan view of the horizontal springs.

A A represent spiral wire springs, the hooks G G thereof being driven into the slats D D for rigidly attaching them thereto in connection with staples F F. These springs are also coiled, as shown, to provide therein the small circles a a in the center of the higher or most enlarged part of the spirals. These small circles, which are located in a vertical line with 35
40 the smaller part or base of the springs, and on the same plane as the top of the bed-bottom, are designed to provide a means of securing the vertical springs in position, when they would otherwise be swayed or distorted
45 from position by pressure. This is effected by means of the horizontal springs B B and links C C, each vertical spring being secured therewith, as shown. The links C C hook into the loops of the horizontal springs, and the horizontal springs are rendered elastic by their 50 loops, whose terminal points are bent into hooks for securing the same to the small circles a a of the spiral vertical springs.

The slats D D rest upon the supporting spiral springs E E, and are guided by the vertical wires b b, which project through orifices in said slats, and transverse bars d d. 55

The hooks G G, that fasten to the slats, as shown, pass over and rest upon the lower coil of the vertical springs, and thus hold them 60 steadfast.

The wires forming the supporting spiral springs are bent at their upper terminal points, after being projected through the transverse bars d d, in such manner as to secure the springs 65 in position and prevent their withdrawal; and these bent ends are concealed by the metallic caps e e, which are provided with the projecting points f f, which are driven vertically into the cross-bars. The vertical supporting-springs 70 are threaded at the upper parts thereof, and are there secured above the cross bars d d by the nuts e e, and they project vertically downward, through orifices provided in said cross-bars and slats D D, to the bottom of the springs, 75 and are there coiled in enlarging convolutions from their lower extremity upward, and finally terminate in the eyes b' b', through which project their vertical stems. These eyes are caused to clutch rigidly the rubber tubes T T, 80 and the tubes encircle the vertical supporting-springs, and are designed to prevent any creaking noise arising from vibration.

By the peculiar construction and arrangement of the parts of my bed-bottom great elasticity is obtained, and in all respects a more durable and comfortable article is produced. 85

What I claim is—

1. The combination of the links C C, horizontal springs B B, and vertical springs A A, 90 substantially as shown, and for the purpose described.
2. The vertical springs A A, secured by the horizontal springs B B and links C C, in combination with the slats D D, cross-bars d d, 95 and supporting-springs E E, substantially as shown and described.

In testimony whereof I affix my signature in presence of two witnesses.

DANIEL B. PECK.
